UNITED STATES PATENT OFFICE.

CLAYTON LE ROY KLISE, OF YANKTON, SOUTH DAKOTA.

AERIAL TORPEDO.

1,343,831.

Specification of Letters Patent. Patented June 15, 1920.

Application filed September 17, 1918. Serial No. 254,474.

To all whom it may concern:

Be it known that I, CLAYTON LE ROY KLISE, a citizen of the United States, residing at Yankton, in the county of Yankton, 5 and State of South Dakota, have invented certain new and useful Improvements in Aerial Torpedoes; and I do hereby declare the following to be a full, clear, and exact description of the invention, such as will 10 enable others skilled in the art to which it appertains to make and use the same.

This invention relates to aerial torpedoes, and more particularly to means whereby a body carrying a relatively large charge of a 15 high explosive may be readily propelled and steered through the air, the charge of explosive being ignited at a predetermined time.

One of the main objects of the invention is to provide a torpedo and steering and propelling means therefor of comparatively 20 simple construction and operation which is so made as to be readily propelled through the air at relatively high speed with but little power.

25 A further object is to provide a torpedo the body of which is so shaped as to provide a head for carrying a relatively large charge of high explosives, the propelling and steering mechanisms being so related as to obtain 30 proper balance of the machine as a whole.

35 A further object is to provide a torpedo comprising a rearwardly tapering body of the so-called torpedo shape, the various steering and propelling mechanisms being positioned within this body so as to be completely inclosed and protected thereby.

Further objects will appear from the detailed description.

In the drawings:

40 Figure 1 is a top plan view of an aerial torpedo constructed in accordance with my invention.

Fig. 2 is a side view of the same.

Fig. 3 is a front view.

45 Fig. 4 is a longitudinal central sectional view, showing the container for the explosive charge and the projectiles as being broken away.

50 Fig. 5 is a section taken substantially on line 5—5 of Fig. 4.

In carrying my invention into effect, I provide a rearwardly tapering body 1 which is of torpedo shape, that is to say the body tapers rearwardly uniformly from the head 55 portion 1^a thereof and is of circular cross section. This body is preferably formed of

some frangible material of relatively great strength, such as thin steel which is highly tempered so as to be readily broken up or shattered by the force of the explosion when 60 the explosive charge carried in head 1^a thereof is exploded. This body 1 is provided, at the tail end thereof, with the vertical and horizontal rudders 2 and 3, respectively, which operate in the well known 65 manner and are connected by suitable connections to the steering and control mechanism designated generally by 4 which is adapted to be actuated by wireless or radiant energy. It will be understood that this 70 control mechanism 4 may be of any suitable or standard construction and may be operably connected to the rudders 2 and 3 in any suitable or preferred manner. This mechanism and the connections between the rudders form no part of my invention except in 75 so far as they coöperate with the means to be hereinafter described to accomplish the desired result. The body 1 is further provided, at the tail end thereof, with a depend-

80 ing arcuate skid 5 which coöperates with supporting wheels 6 carried by brackets 7 at the forward or head end of the body, to support the body in such manner as to permit ready movement thereof over the 85 ground surface. A sheet metal compressed air tank 8 is mounted in body 1 adjacent the tail portion thereof, this tank being provided with a valve 9^a which is normally closed by a valve cap 9, and with a pressure 90 gage 10. The tank 8 is connected by an air supply pipe 11 to an air motor 12 of suitable construction, a suitable valve 13 being interposed in this pipe and provided with a stem 14 which projects through the top of body 95

1, this stem having a hand wheel 15 on its upper end. By means of this valve 13, supply of air to the motor from tank 8 may be readily controlled. The propeller shaft 16 of the motor projects both rearwardly and 100 forwardly thereof, and is provided at its rearward end with a bevel pinion 17 secured thereon and meshing with a bevel gear 18 secured on the shaft 19 of a gyroscope 20. Drive shaft 16 of the motor is provided, at 105 its forward end, with a spur pinion 20 secured thereon meshing with a spur gear 22 secured on a propeller shaft 23 which is rotatably mounted adjacent its inner end to an upright 24 secured to the body. This propeller shaft is rotatably supported through an elongated bearing tube or sleeve 25 ex-

tending centrally of an explosive container 26 which fits snugly in the head portion 1^a of the body and conforms in shape thereto. The shaft projects beyond the nose 1^b of the 5 body and is provided, at its forward end, with a propeller 27 of suitable type secured thereon. By opening valve 18 so as to supply air which is stored in the tank 8 under pressure to the motor 12, propeller 27 may 10 be rotated at relatively high speed so as to propel the torpedo through the air, the torpedo being guided by means of the rudders 2 and 3 which are controlled by radiant energy in any suitable manner, gyroscope 20 15 acting to maintain the body on an even or level keel during its passage through the air.

To facilitate passage of the body 1 through the air, I provide at each side thereof a laterally projecting plane 28 of any suitable or standard construction which is connected to a bracing post 29 projecting above the body by guy wires 30, and to the sides of the body by rearwardly extending guy wires 25 31. These planes are secured, at their inner ends, to the upper ends of uprights 32 projecting from a cross piece 33 which connects the upper ends of frames or brackets 7 carrying the ground wheels 6 and forms there- 30 with and with the uprights 32, a rigid frame which is secured, by means of the uprights, to the body 1, this frame acting to maintain the body and the planes in proper relation to each other.

35 The explosive container 36 comprises an outer casing or shell 34 and an inner casing 35 disposed in concentric spaced relation thereto. The inner casing forms a container or receptacle for an explosive charge designated by 36, the explosive used being preferably of great power or what is commonly termed a high explosive. The space between the inner shell 35 and the outer shell 34 constitutes a chamber which receives a plurality of projectiles such as shrapnel shot indicated by 37. The casings 34 and 35 are provided with aligned openings which receive a time fuse 38 tightly secured therein and projecting into the inner casing, this fuse serving to ignite the explosive charge 36. In practice, the length of this fuse will depend upon the distance which the torpedo is to travel before being exploded, as will be readily understood.

55 To reduce weight to a minimum, the engine or motor 12 and associated parts are, preferably, constructed of aluminum or other suitable relatively light material, though it will be understood that any material may be employed. As will be noted, the various operating and steering mechanisms are disposed in alignment of the body and

are completely contained thereby so as to be protected against injury. In addition, these mechanisms are so disposed as to secure proper balancing of the body so as to permit easy passage thereof through the air in a horizontal position. In practice, the time fuse 38 is ignited and valve 18 is opened simultaneously therewith so as to cause the 70 torpedo to be propelled through the air, it being understood, of course, that the torpedo is first sighted in the direction in which it is desired to have it travel. The torpedo is maintained on a level or even keel by 75 means of the gyroscope 20, and it may be readily steered through the air through the medium of the controlling apparatus designated generally by a associated with the rudders 2 and 3. In this manner, the torpedo containing the relatively large charge of high explosive may be brought into the desired position, after which it is exploded by means of the time fuse 38. When the torpedo is exploded, the shrapnel 37 will be 80 projected outwardly therefrom in all directions thus doing great execution in the enemy ranks if the torpedo is used for attacking troops. Also, the force of the explosion itself will serve to do great damage 85 to fortifications and earth works adjacent which the torpedo is brought before being exploded.

It will be evident that there may be slight changes made in the construction and arrangement of the details of my invention without departing from the field and scope of the same, and I intend to include all such variations, as fall within the scope of the appended claim, in this application in 90 which a preferred form only of my invention is disclosed.

What I claim is:

In an aerial torpedo, a rearwardly tapered body provided in its forward end portion 105 with an elongated container for an explosive charge, means for exploding said charge at a predetermined time, a propeller shaft projecting forwardly of said body through the container, a propeller secured thereon, a compressed air tank in the rear portion of the body, a gyroscope in the body in front of the tank, and a motor in the body between the gyroscope and container and having connection with the gyroscope and propeller shaft for imparting movement to the same.

In testimony whereof I affix my signature in presence of two witnesses.

CLAYTON LE ROY KLISE.
